METHODS OF APPLYING INDICIA TO
ROUNDED SURFACES OF SMALL RADIUS

George W. Angerstein, Chicago, Ill.

Application October 13, 1933, Serial No. 693,441

4 Claims. (Cl. 101—35)

The present invention relates to methods of applying indicia to rounded surfaces of small radius.

More particularly the present invention relates to methods of applying indicia to marbles or the like, or other spheres, and has for one of its objects the provision of a method of applying pigment or other distinctive matter to a rounded surface which is of such small radius as to present practical difficulties to the use of methods commonly used in the ceramic arts.

A further object is to provide a method of applying indicia to a small sphere in which the matter of handling the sphere and the indicia is greatly simplified.

A further object is to provide a method of applying indicia to a small sphere which will permit handling on a quantity basis and which will be cheap and well adapted to commercial manufacture.

A further object is to provide an improved structure for carrying out a step of the method above referred to.

Further objects will appear as the description proceeds.

Referring to the drawing—

Figure 1 represents in top plan a preferred construction which may be used in the practice of the present invention; and

Figure 2 represents a sectional view taken along the plane 3—3 of Figure 1.

The present invention contemplates the burning on of indicia upon rounded surfaces of small radius such as the ordinary marbles used by children in playing games. Such articles are of course subjected to rough treatment, and attempts to apply advertising matter to marbles according to processes heretofore known have failed for the reason that they did not produce permanent results or were prohibitively expensive. The present invention is particularly useful in connection with marbles of popular sizes, as for example those which have a diameter of approximately $\frac{1}{2}$ inch, $\frac{3}{8}$ inch, or $\frac{3}{4}$ inch, though the invention is also applicable to marbles of the larger sizes, as for example those approximately 1 inch, $1\frac{1}{2}$ inches and 2 inches in diameter.

It has been suggested that indicia be applied to marbles or the like by means of sand-blasting, a mask being used to protect those portions of the marble which are not to be sand-blasted. This method is expensive, inasmuch as the force of the sand is destructive to the mask, and is not at all practical in connection with small

marbles upon which it is desired to apply lettering, inasmuch as the sand-blast soon cuts out the connecting portions between the letters of the mask, completely destroying the mask.

It has also been suggested that an etching process be used, but this is prohibitively expensive and involves difficulties in handling small articles.

A further suggestion, and one which falls within certain aspects of the present invention, is to use a decalcomania method. This method has certain objections due to the fact that sizing of the base is required, and the presence of this sometimes results in running or crazing, that is—crazing, or cracking of the material forming the indicia, in the event that firing is not slowly and uniformly performed. However, as will be clear from the description which follows, a decalcomania process may be used in the practice of the present invention if firing is correctly carried out.

According to methods at present preferred, the present invention is carried out by applying the indicia, in the form of pigment, suspended in a heavy fatty oil, as for example boiled linseed oil or sandalwood oil. Those skilled in ceramic arts will find a wide field of choice among the oils or other conveyers suitable for the purpose, and of course the identity of various pigments suitable for burning upon marbles are well known. The particular oil or conveyer for the pigment should evaporate readily, leaving only the pigment as a residue, at temperatures between 100 and 150 degrees F., though oils or other conveyers which evaporate at higher temperatures may be used if preferred, so long as they evaporate without thinning out. It is essential in the practice of the present invention that the oil or other conveyer for the pigment should deposit the pigment suspended therein as a residue when evaporation of such oil or other conveyer occurs without the carrying away of such pigment by the "running" of the oil or other conveyer.

The matter of applying the indicia in its conveyer of oil or the like may be accomplished by an offset process, as for example by applying a mixture of oil and pigment by means of a rubber stamp; or said oil or other conveyer free of the pigment may be applied to the base by means of a rubber stamp, after which the pigment in the form of powder or dust is sprinkled upon said oil. The pigment may be any of those well known to the worker in ceramics. For fine work, the heavier the oil and the finer the powder or dust the more clean-cut will be the resulting indicia.

- The preferred construction for applying indicia to the marble is illustrated in Figures 1 and 2. The structure shown in these figures involves a block 7, a portion of the upper surface thereof being dished to form a depression 8. Said depression 8 is defined by a rounded surface 9, which may be a portion of a spherical surface the radius of which is materially greater than the radius of the marble to be operated upon. Disposed upon the upper surface of the block 7 is the mat 10 of rubber or equivalent material. The block 7 may have secured thereto corner pieces 11—11 extending upwardly beyond the upper surface of said block 7 to removably hold the mat 10 in position upon said block 7. The mat 10 should be flexible and resilient and should preferably be unattached to the block 7, whereby when a marble is pressed downwardly upon the mat 10 at the region above the depression 8, said mat 10 may slide upon the upper surface of the block 7.
- In using the structure shown in Figures 1 and 2, the indicia in its conveyer of oil or the like will be applied to the portion of the mat 10 above the depression 8. For the purpose of applying said indicia to the mat 10, a matrix, wood cut, or the like, may be used. The marble, held against rotation, will be pressed downwardly on the mat 10, which will yield under said pressure. Inasmuch as the mat 10 is free to slide upon the block 7, there will be a minimum of distortion of the indicia.
- Other means of applying the pigment will occur to those skilled in the art.
- After the pigment, carried by the oil or other conveyer, has been applied in the design desired upon the marble or other article, said marble or other article is subjected to a firing temperature, the temperature being gradually raised, particularly in the early stages of the firing operation.
- The slow increase in temperature has two purposes, one being to permit the evaporation of oil or other conveyer without cracking or crazing, whereby the pigment will be properly deposited upon the surface of the marble or the like. The gradual rise in temperature has the further purpose of raising the temperature of the marble uniformly, thereby avoiding distortions in the surface of the marble which would cause cracking and crazing, distorting the indicia before the pigment had fused with the surface of the marble.

The fluid used as the conveyer must, according to the present invention, provide the bond between the pigment and the marble surface, and should evaporate at a temperature well below the fusing point between the pigment and the marble. As indicated above, the fluid used as a conveyer should completely evaporate and deposit the pigment before running occurs. 80

Many modifications of the above description will occur to those skilled in the art. It is intended to cover all such modifications that fall within the scope of the appended claims. 85

What is claimed is—

1. The step in the method of applying indicia to an article having a rounded surface of small radius which consists in applying pigment according to a predetermined design to the surface of a yieldable resilient mat, supporting said mat except at the region of said pigment while permitting it to slide, applying said article to said pigment, and stopping movement of said mat in opposition to the movement of said article at a region spaced from the region of support of said mat. 90

2. Apparatus for applying indicia to an article having a rounded surface of small radius comprising, in combination, a block having a rounded depression in a surface thereof and a pliable resilient mat slidably supported upon said surface, said mat overlying said rounded depression. 100

3. Apparatus for applying indicia to an article having a rounded surface of small radius comprising, in combination, a block having a rounded depression in a surface thereof and a pliable resilient mat slidably supported upon said surface, said mat overlying said rounded depression, said block being provided with means for limiting sliding movement of said mat relative to said block. 110

4. Apparatus for applying indicia to an article having a rounded surface of small radius comprising, in combination, a block having a rounded depression in a surface thereof and a pliable resilient mat slidably supported upon said surface, said mat overlying said rounded depression, the radius of said rounded depression being relatively large as compared with the radius of the rounded surface of said article. 115
